UNITED STATES PATENT OFFICE.

JOSEPH M. SCHUTZ, OF MINNEAPOLIS, MINNESOTA.

DESIGN FOR AN INCENSE-BURNER.

No. 38,142.

Specification for Design.

Patented July 31, 1906.

Application filed May 25, 1906. Serial No. 318,788. Term of patent 7 years.

To all whom it may concern:

Be it known that I, JOSEPH M. SCHUTZ, a citizen of the United States, residing at Minneapolis, in the county of Hennepin and State of Minnesota, have invented a new, original, and ornamental Design for Incense-Burners, of which the following is a specification, reference being had to the accompanying drawing, forming part thereof.

The figure is an elevation of an incense-burner showing my design.

I claim—

The ornamental design for an incense-burner, as shown.

JOSEPH M. SCHUTZ.
